(57) **CLAIM**

The ornamental design for mini secure digital card connector, as shown and described.

DESCRIPTION

FIG. 1 is a perspective view thereof;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, on a reduced scale.

The broken line drawing of a digital card in FIG. 8 is for illustrative purposes only and forms no part of the claimed design.
